REFRIGERATING APPARATUS

Clarence W. Kuhn, Wauwatosa, Wis., assignor to
Cutler-Hammer, Inc., Milwaukee, Wis., a corporation of Delaware

Application April 26, 1937, Serial No. 138,927

6 Claims. (Cl. 62—4)

This invention relates to refrigerating apparatus and more particularly to control mechanisms for such apparatus.

Electric refrigerators are usually controlled by a device having adjustable cold control means associated therewith for maintaining the cooling unit of the refrigerator at selected temperature values such as are required for ordinary refrigerating purposes. In some instances such control devices are also provided with semi-automatic control means including manual control means for rendering the device effective to raise the temperature of the cooling unit to a given value for defrosting or to lower the temperature thereof to a given value for quick freezing and automatic means for restoring the control device to normal condition upon attainment of such temperature values.

The present invention has among its objects to provide a refrigerator control device of the aforesaid character having a simplified and generally improved semi-automatic defrosting and quick freeze control mechanism associated therewith.

Another object is to provide a control device of the aforesaid character in which a single loading spring serves to effect cold control and also semi-automatic quick freeze and defrost control.

Another object is to provide a control device of the aforesaid character which provides a fixed defrosting temperature and a fixed quick freeze temperature regardless of the setting of the cold control means.

Various other objects and advantages of the invention will hereinafter appear.

The accompanying drawing illustrates an embodiment of the invention which will now be described, it being understood that various modifications may be made in the embodiment illustrated without departing from the spirit and scope of the appended claims.

In the drawing,

Figure 1 is a side view of a refrigerator control device embodying the invention, a portion of the enclosing casing being broken away and portions of the operating mechanism being shown in section.

Figs. 2 and 3 are fragmentary side elevational views of the control device shown in Fig. 1 illustrating the semi-automatic control means in defrosting and quick freeze positions, and

Figs. 4 and 5 are fragmentary sectional views taken substantially on lines 4—4 and 5—5 respectively of Fig. 1.

Referring to Fig. 1, the invention is shown in

connection with a refrigerator control device of the type shown in my copending application Serial No. 708,804, filed January 29, 1934, but it may be used in connection with control devices of other types.

Briefly the refrigerator control device shown in Fig. 1 includes a box enclosing casing 1 having a switch unit 2 and a fluid condition responsive device 3 mounted therein. Said switch unit includes an insulating base 4 which carries a pivoted bridging contact element 5 and a pair of cooperating stationary contacts, one of which is illustrated at 6. Contact element 5 is movable with a snap action into and out of engagement with its cooperating stationary contacts by an over center spring 7, said spring being operatively connected to an operating knob 8 slidably mounted within an opening in the front wall of casing 1. The switch unit 2 also has a free tripping overload mechanism associated therewith which acts under overload conditions to move contact element 5 into open position through the medium of the spring 7 and which is resettable by the knob 8. However, the overload mechanism need not be considered for the purpose of this application.

The fluid condition responsive device 3 includes a bellows 10 secured to the rear wall of casing 1 and having a connecting pipe extension 11 on the rear end thereof. The pipe 11 may be connected to the low pressure side of the refrigerator to provide for operation of the bellows by pressure in that part of the apparatus or it may contain an expansible gas and be arranged at a point contiguous to the cooling unit of the refrigerator where the temperature and consequently the pressure within the pipe and bellows varies in accordance with operations of the refrigerator.

The front end of bellows 10 bears against a lever 12 having a vertically arranged arm 12^a which is pivoted at 13 upon a bracket 14 fixed within the casing 1. A loading spring 15 engages arm 12^a of lever 12 to oppose expansive movements of the bellows 10 and said lever has a snap operating mechanism associated therewith for moving bridging contact 5 into and out of circuit closing position. Such operating mechanism includes a lever 17 pivoted at 18 upon bracket 14 and an over center spring 19 which is held under compression between the free end of arm 12^a and the free end of lever 17. Movement of lever 17 is limited in one direction by insulating base 4 and in an opposite direction by an adjustable stop 20 secured to the rear wall

of casing 1 and said lever is arranged to operate the movable contact element 5 through the medium of an insulating member 21 slidably mounted within a recess in insulating base 4.

5 Upon a decrease in temperature, bellows 10 contracts under the action of spring 15 and for a given low temperature value determined by the degree of compression of spring 15 lever 12 assumes a position wherein the axis of spring 19 10 is located to the left of pivot 18 whereupon lever 17 is moved with a snap action out of the position shown in Fig. 1 to effect opening of bridging contact 5 against the action of spring 7. Upon an increase in temperature, bellows 10 expands against the action of spring 15 and for a given high temperature value also determined by the setting of spring 15 lever 12 assumes a position wherein the axis of spring 19 is located to the right of pivot 18 whereupon lever 17 moves 15 with a snap action into the position shown in Fig. 1 to permit reclosure of contact element 5 under the action of spring 7. As is apparent, increasing the degree of compression of spring 15 raises the temperature values at which contact element 20 25 5 is moved into circuit closing and circuit opening positions, while decreasing the degree of compression of said spring has an opposite effect.

Spring 15 is held under compression between arm 12^a of lever 12 and a lever 22 which is pivotally mounted as shown at 23 upon the upper wall of casing 1. Lever 22 bears against a nut 24 carried by a screw 25 rotatably mounted within an opening in the front wall of casing 1. Nut 24 is held against turning by a rib 26 on casing 1 30 which engages within a recess in said nut and screw 25 is held against forward movement under the action of spring 15 by a shoulder 27 thereon which engages the front wall of casing 1. The front end of screw 25 has a dial pointer 28 fixed 35 thereto, and as is apparent the screw 25 is adjustable by the dial pointer 28 to adjust nut 24 and lever 22 axially with respect to said screw for variation of the degree of compression of loading spring 15. The dial pointer 28 is movable 40 over a suitable dial which may be formed on the front face of casing 1 to indicate the setting of loading spring 15, and as is the usual practice said dial pointer has a limited range of adjustment to provide for starting and stopping 45 of the refrigerator at selected temperature values within a given normal range.

The above described control device is provided with a semi-automatic defrost and quick freeze control mechanism. Such mechanism includes a control lever 32 having an enlarged hub 33 which is arranged within an opening in the front wall of casing 1 and is rotatably mounted upon a pin 34 carried by said casing. As shown in Fig. 5, lever 12 is provided with 50 spaced forwardly extending arms 12^b and 12^c which are located on opposite sides of the hub 33 on control lever 32, and said hub is provided with spaced slots for receiving a pair of links 35 and 36. Links 35 and 36 have their front 55 ends pivotally secured to hub 33 by pins 37 and 38 respectively, and each of said links has a slot on its inner end for receiving a pin 39 fixed to lever 22. Pin 37 is arranged below arm 12^b of lever 12 and is provided with a projection 37^a for engaging said arm on the under side thereof. Pin 38 is arranged above the arm 12^c and is provided with a projection 38^a for engaging said arm on the upper side thereof.

With control lever 32 in the position shown 70 in Fig. 1 the pivot pin projections 37^a and 38^a

are spaced with respect to their associated arms 12^b and 12^c to permit unobstructed movement of lever 12 between positions for opening and closing contact element 5. Also with control lever 32 in the position shown in Fig. 1 pin 39 on lever 22 slides within the slots on the inner ends of links 35 and 36 upon adjustment of said lever by dial pointer 28.

Control lever 32 is movable out of the position shown in Fig. 1 into a defrost position wherein 10 the same engages a stop surface 41 on the front wall of casing 1. Upon movement of control lever 32 into defrost position link 36 engages pin 39 on lever 22 to move said lever away from nut 24 into the position shown in Fig. 2. Spring 15 is thus compressed to increase the loading effect thereof, and as is apparent from Fig. 2 link 36 is so located that control lever 32 is yielding held in engagement with stop surface 41 under the action of said spring. Also 20 upon movement of control lever 32 into defrost position pin projection 38^a engages the upper side of arm 12^c of lever 12 to move said lever into circuit opening position if the same is not already in such position. Lever 12 remains in 25 circuit opening position under the action of spring 15 until the temperature of the refrigerator rises to a given abnormal value which is sufficiently high to effect defrosting of the cooling unit. When the temperature rises to 30 such abnormal temperature value bellows 3 acts against the action of spring 15 to move lever 12 out of the position shown in Fig. 2. Arm 12^c of lever 12 then engages pin projection 38^a to move control lever 32 towards off position, and as is 35 apparent upon a slight movement of said control lever out of defrost position link 36 assumes a position wherein said control lever is returned with a snap action to off position under the action of spring 15. Upon return of control 40 lever 32 to off position lever 12 moves into its circuit closing position to restart the refrigerator and lever 22 moves into engagement with nut 24 to render the control device operative to maintain the temperature of the refrigerator between 45 temperature limits determined by the setting of dial pointer 28.

Control lever 32 is also movable out of the position shown in Fig. 1 into a fast freeze position 50 shown in Fig. 3. Upon movement of control lever 32 into its fast freeze position the link 35 engages pin 39 on lever 22 to move said lever away from nut 24 into the position shown in Fig. 3 and the projection 37^a of pivot pin 37 engages the under side of arm 12^b to move 55 operating lever 12 into its circuit closing position if the same is not already in such position. With control lever 32 in its fast freeze position spring 15 acts through the medium of link 35 to bias said control lever in a clockwise direction whereby the pivot pin projection 37^a acts on arm 12^b to exert an upward pressure thereon. The upward pressure on arm 12^b opposes the force exerted by spring 15 on arm 12^a, and the parts are so designed that the pressure on arm 60 12^b reduces the loading effect of spring 15 on lever 12 to an abnormally low value. Lever 12 remains in the circuit closing position shown in Fig. 3 until the temperature of the refrigerator drops to a given abnormal quick freezing temperature. Bellows 3 is then compressed under the action of spring 15 and the arm 12^b of lever 12 acts through the medium of pin projection 65 37^a to move control lever 32 towards off position. As is apparent, upon a slight movement 70 75

of control lever 32 out of fast freeze position link 36 is moved into a position wherein said control lever is returned with a snap action to off position under the action of spring 15. Upon return of control lever 32 to off position the loading effect of spring 15 upon lever 12 is increased and said lever moves into switch opening position to stop the refrigerator. Also lever 22 moves into engagement with nut 24 to provide for operation of the refrigerator at temperature values determined by the setting of dial pointer 28.

In connection with the foregoing it should be noted that when control lever 32 is in either its defrosting or fast freeze position the same can be manually moved to off position at any time to restore the control device for operation in accordance with the setting of dial pointer 28. Also it should be noted that opening and closure of contact element 5 by control lever 32 is effected with a snap action.

What I claim as new and desire to secure by Letters Patent is:

1. In a refrigerator control device, in combination, a switch, thermo-responsive operating means therefor, a single loading spring associated with said thermo-responsive operating means, an adjustment control for varying the effect of said loading spring to provide for operation of said switch at selected temperature values within a given normal range, and mechanism for varying the loading effect of said spring to provide a given operation of said switch at a predetermined abnormal temperature value outside of said normal range regardless of the setting of said adjustment control.

2. In a refrigerator control device, in combination, a switch, thermo-responsive operating means therefor, a single loading spring associated with said thermo-responsive operating means, an adjustment control for varying the loading effect of said spring to provide for operation of said switch at selected temperature values within a given normal range, and means for varying the loading effect of said spring to provide a given operation of said switch at a predetermined abnormal temperature outside of said normal range and for restoring said spring to the setting determined by said adjustment control upon operation of said switch at said predetermined abnormal temperature.

3. In a refrigerator control device, in combination, a switch, temperature responsive operating means therefor having a single loading spring associated therewith, an adjustment control for varying the loading effect of said spring to provide for operation of said switch at selected temperatures within a given normal range, manual means for increasing the loading effect of said spring to provide for closure of said switch at a predetermined defrosting temperature outside of said range, and means for restoring said manual means to normal position upon opening of said switch at said predetermined defrosting temperature.

4. In a refrigerator control device, in combina-

tion, a switch, temperature responsive operating means therefor, a loading spring associated with said temperature responsive operating means normally set to provide for operation of said switch at temperature values within a given normal range, manual means for varying the loading effect of said spring to selectively provide for operation of said switch at different predetermined abnormal temperatures outside of said range, and means for restoring said manual control means to normal condition upon operation of said switch at either of said abnormal temperatures.

5. In a refrigerator control device, in combination, a control switch, temperature responsive operating means therefor, a single loading spring associated with said temperature responsive operating means, an adjustment control for varying the loading effect of said spring to provide for operations of said switch at selected temperatures within a given normal range, a control part movable between off and defrost positions, mechanism actuated upon movement of said control part into its defrost position for modifying the loading effect of said spring to provide for closure of said switch at a substantially fixed defrosting temperature outside of said normal range, said control part when moved into defrost position being releasably held therein by said mechanism under the action of said loading spring, and means associated with said temperature responsive operating means for moving said control part out of defrost position upon closure of said switch at said substantially fixed defrosting temperature.

6. In a refrigerator control device, in combination, a control switch, temperature responsive operating means therefor, a single loading spring associated with said temperature responsive operating means, an adjustment control for varying the loading effect of said spring to provide for operation of said switch at selected temperatures within a given normal range, a control part movable in opposite directions out of an intermediate off position into extreme defrost and fast freeze positions, mechanism uninfluenced by the setting of said adjustment control and associated with said control part for modifying the loading effect of said spring to provide for closure of said switch at a substantially fixed defrosting temperature outside of said normal range upon movement of said control part in its defrost position and for opening of said switch at a substantially fixed fast freeze temperature outside of said normal range upon movement of said control part into its fast freeze position, said control part when moved into its defrost or fast freeze positions being releasably held therein by said mechanism under the action of said spring, and means associated with said temperature responsive operating means for returning said control member to off position upon operation of said switch at said defrosting or fast freeze temperatures.

CLARENCE W. KUHN. 65
